UNITED STATES PATENT OFFICE

2,305,670

MACHINE FOR ASSEMBLING SHOE PARTS

Joseph C. Cantley, Beverly, Mass., assignor to
 United Shoe Machinery Corporation, Flemington, N. J., a corporation of New Jersey

Application February 28, 1942, Serial No. 432,762

53 Claims.

(Cl. 12—17)

This invention relates to machines for use in assembling and molding shoe parts and is illustrated as embodied in a machine for relatively positioning and securing together the component parts of reinforced insoles and for performing a molding operation upon the insole. It is to be understood, however, that the invention and various important features thereof may have other applications and uses.

It is an object of the invention to provide for the positioning of the constituent parts of an article relatively to each other and for the gaging of article parts with respect to work treating elements of the machine, so that the article may be perfectly formed during a machine operation which follows the assembling of the parts, and to do this in such a way that the gaging and positioning operations may be effectively performed in spite of adjustment and/or alterations in the work treating mechanism made to suit variations in the method of assembly of the parts of the article. It is a further object of the invention to provide for a combined manual and automatic control of work positioning and gaging elements from a single treadle or other manually operable member although separate sets of such gaging and positioning elements are provided for each unit of a twin machine.

In the illustrated construction, which in its more specific aspects is an improvement upon the assembling and molding machine disclosed in United States Letters Patent No. 2,151,974 granted March 28, 1939, upon an application of Frank Kennison and Frank E. Stratton, means is provided for projecting work positioning and gaging members into the space between upper and lower molding elements for the assembled work piece and for withdrawing such positioning and gaging members successively in a lateral (i. e. in a sideways direction with respect to the machine) and in an upward direction, thereby avoiding any disturbance of the various work pieces assembled in proper relation to each other as a preliminary to the molding operation. Conveniently, a cam mechanism is so located and so conditioned preliminarily to both the projective and retractive movements of the positioning and gaging members as to control such movements of the latter, that is, into and from their operative positions. In the illustrated construction, the said cam mechanism comprises a cam which is lowered to its operative position prior to the retractive movement of the work positioning and gaging members and which remains in its operative position to insure the described withdrawal movement of such work positioning and gaging members out

of the path of the relatively movable molding elements of the machine.

It is an important feature of the invention that gripping means is provided for holding a work piece, in this case an insole member, in position against a gage member, the purpose being to prevent displacement of the insole member during the molding operation which follows. Conveniently, the gripper means is operated by hydraulic means under control of the operator, the construction being preferably such that the work positioning and gaging members are also operated by the same hydraulic means but at a later time in the cycle of operations as determined by successive movements of a manually controllable member. By providing for control of the hydraulic means in successive steps by the manually controllable member, it is possible for the operator to assemble successively different portions of the article with the aid of work positioning and gaging members moving successively to operative position under control of said manually controllable member.

Another feature of the invention relates to the provision of sets of work positioning and gaging members in association with each unit of a twin work treating machine in an arrangement in which such sets of members are operated selectively from a single manually controllable member. In a preferred construction, the last-mentioned member is movable manually in successive steps for operating in succession a number of work positioning and gaging members.

These and other important features of the invention and novel combinations of parts will now be described in detail in the specification and then pointed out more particularly in the appended claims.

In the drawings,

40 Fig. 1 is a view in front elevation of a twin molding machine for operating upon right and left shoe part members;

Fig. 2 is a view, partly in section, of the hydraulic controlling and operating means for both the shoe part positioning and the molding mechanisms;

Figs. 3 to 8, inclusive, are views showing details of the hydraulic mechanism of Fig. 2;

Fig. 9 is a view in front elevation, and partly in section, of the right side of a machine similar to that shown in Fig. 1, showing a modification of work supporting and positioning elements for "reverse" work, such elements shown enlarged and in more detail;

55 Fig. 9a is a fragmentary view in longitudinal section of a reinforced insole the parts of which

have been assembled, secured together and molded by the use of my machine;

Fig. 10 is a view in side elevation of the machine shown in Fig. 9 looking from a point at the right of the machine;

Fig. 11 is a transverse horizontal section through the machine taken just above the work supporting and positioning means whereby the latter are shown in plan view;

Fig. 12 is a detail view of parts shown in Fig. 11 looking in the direction of the arrow XII in said figure;

Fig. 13 is a detail view of parts shown in the upper part of Fig. 20 looking in the direction of the arrow XIII in said figure;

Fig. 14 is a detail view of work positioning and gaging members;

Figs. 15 and 15a are detail views of latch means also shown in Fig. 14;

Fig. 16 is a detail of an ejector mechanism for disposing of the finished work piece;

Figs. 17, 18 and 19 are detail views of a gage and of a gripper means for holding a work piece against the gage; and

Fig. 20 is a view similar to Fig. 9 but showing a different arrangement of the work supporting and positioning members for "regular" work, Fig. 20 being in fact a view in front elevation of the right side of the machine of Fig. 1 showing the elements enlarged and in more detail.

In the machine illustrated in Fig. 9, which is specially designed for assembling and molding operations upon the constituent parts of a reinforced insole or "insole unit," there is provided a lower mold member 24 in the form of a rubber pad so that certain portions of the work piece may be pressed into the surface of such pad during a molding operation which takes place upon downward movement of an upper mold member 26 of unyielding material such as wood. For cooperation with the lower mold member 24 in supporting and positioning a work piece there is provided a work supporting member 28 adapted to support a toe gage 30 (Figs. 9, 11, and 18) and gripper members 32 for the toe end of an insole 34 when the latter is in position against the gage 30. As shown in Figs. 11 and 18, the gage 30 is arranged at an angle, other than a right angle, with respect to the longitudinal axis of the work support, the gage of Figs. 11 and 18 being for "rights" while the gage of the other molding press will be at an angle (the reverse of Fig. 11) for "lefts." These parts are designed to support and position the constituent elements of a reinforced insole when the latter are being assembled and operated upon in what may be termed "reverse" Unishank work, i. e. for assembling and molding Unishank insole units in which the steel shank and the fiber reinforcing piece are applied to the inner or foot-facing side of the insole (Fig. 9a). In the method of assembly of the parts of a Unishank insole upon the mold member 24 and the work support 28 (Fig. 9), the insole 34 (Figs. 9 and 9a) is placed upon the members 24, 28 with the toe end of the insole member against the exposed face of the gage 30. Then, upon a suitable depression of a treadle 36 (Figs. 2 and 4) against a spring 37, the gripper members 32 are caused to engage the toe end of the insole 34 to hold the latter in place by clamping it against the support 28, since it might otherwise be displaced at the beginning of the molding operation which takes place during downward movement of the wooden mold member 26 carried by the movable head 21. Such tendency

to displacement would be due in part, at least, to compression of the rubber pad under pressure of wooden member 28. In the next step in the assembly of the Unishank insole, a steel shank member 38 (Figs. 9 and 9a) is placed upon the insole member 34, said member being located on the insole member with the aid of a shank positioning member 40 (Figs. 9, 14 and 15) which was brought down into contact with the insole member 34 as a result of the first depression of the treadle member 36. As shown in Fig. 15, the end of the member 40 is forked to receive the shank member 38 and position the same in both endwise and lateral directions with respect to the insole 34. A further downward movement of the treadle 36 brings down a holdown 42 which presses on the top surface of the steel shank 38 at a point adjacent to the operative end of the positioning member 40. There is then placed on top of the steel shank 38 a reinforcing member 44 which, at its forward end, rests on the operative end of the holdown 42. This makes it desirable that both the positioning member 40 and the holdown 42 be withdrawn in a direction lengthwise of the insole before the upper mold member 26 comes into contact with the parts to be molded. As indicated above, means is provided for retracting the positioning member 40 and the holdown 42 first in a substantially lateral direction i. e., in a direction substantially lengthwise of the insole parts and then in an upward direction prior to the molding operation on the assembled insole parts. In the illustrated construction, this means comprises a supporting structure for the members 40, 42 shown in detail in Figs. 9, 10 and 13 to 15, inclusive. As shown, the positioning member 40 is carried by a slide member 48 to the lower end of which it is secured by a set screw 41. The slide member 48 has a projection 48a and is mounted for vertical sliding movement in a housing 49 adjustable by a set screw 49a (Fig. 14) on a carrier 50 in turn mounted for swinging movement on a pintle 52 rigidly supported by a slide 54 in frame member 55 which overhangs the work supporting member 28. To provide for relative movement between the positioning member 40 and the holdown 42, the latter is slidably mounted in a guideway in the slide member 48 (Figs. 14, 15, 15a) back of a face plate 57 on the front of the housing 49. To hold the members 40, 42 yieldingly in their lowermost positions, each member is provided with a pin 59 to which is attached an extensible spring 61, the lower ends of the spring 61 being attached to other pins 63 fastened to the housing 49. At its upper end, the holdown 42 is provided with a pin 65 (Figs. 15 and 15a) which engages the upper edge of the face plate 57 to limit downward movement of the holdown 42 under the pull of the spring 61. However, the holdown can move upwardly against the tension of spring 61. Slide member 48 which carries member 40 is limited in its downward movement by the projection 48a at its upper end engaging the upper edge of a portion of housing 49, such slide member being movable upwardly against the pull of its spring 61. At a certain point in its upward movement the slide member 48 lifts member 42 by contact with pin 59 carried by the latter member as shown in Fig. 15. At about said point both members 40, 42 are locked in their retracted positions after they have been lifted by contact with the assembled work pieces, the locking being effected by engagement of the nose end 67 of a latch member 69 under said projection 48a on the slide member

48 when the latter has been lifted in the manner described, the movement of the latch member 69 being caused by a compression spring 71 (Fig. 15a). This is an important feature of the construction of the supporting devices for the positioning member 40 and the holdown 42, since latching them in their relatively raised positions just described minimizes the possibility that they will be dragged over the surfaces of the assembled work pieces while being retracted laterally just before the molding operation. It should be noted in this connection, that the members 40, 42 are later released from the latch member 69. This takes place when the said members 40, 42 together with their supporting means return to their uppermost positions of rest shown at the right in Fig. 1 and in Fig. 20. The unlatching occurs when the tail part of latch member 69 comes in contact with the stationary abutment 73.

For moving the carrier 50, together with the members 40 and 42, toward and from the lower mold member 24 there is provided a lever 70 (Figs. 10 and 13) pivoted at 72 on the frame member 55, said lever 70 being pivotally connected to the lower end of the slide 54 by links 74, said lever 70 being normally held in its uppermost position by a spring 76 and being movable between its uppermost and its lowermost positions as determined by set screws 78 and 80 mounted in a flange in said frame member 55. For operating the lever 70, and hence the slide 54 and the members 40, 42 there is provided a connecting rod 82 and a hydraulic mechanism (hereinafter described) under control of the treadle member 36 (Figs. 2 and 4). Downward movement of the treadle 36 will depress the slide 54 and carrier 50 and successively bring the positioning member 40 and the holdown 42 into their respective positions shown in Figs. 9 and 15. It will be readily understood that as the carrier 50 and the members 40, 42 are moved downwardly by the lever 70, the positioning member 40 will contact the insole 34 first and yield upwardly relatively to the holdown 42, causing tension of its spring 61. The next downward movement of the treadle 36 and lever 70 will cause further retraction of the member 40 until holdown 42 is reached and shoved upwardly against the tension of its spring by contact with the shank piece 38 (Fig. 15).

As shown in Figs. 1, 9, 14 and 20, the carrier 50 is provided with a cam roll 102 adapted to be received and guided in a cam groove 104 formed in a cam member 106 slidable vertically in the head 55 and normally held in its uppermost position through an extensible spring 108 (Fig. 13). Conveniently, the carrier 50 for the positioning and holdown members 40, 42 is provided with an arm 109 (Figs. 9, 13 and 20) in which is mounted a set screw 111, the latter being adapted to engage a surface 113 at the upper end of the slide member 106 to move the latter downwardly against the yielding resistance of the spring 108, it being understood in this connection that the carrier member 50 is swung from its inclined position (Fig. 20) (which represents its uppermost position of rest) to a vertical position (Fig. 9), this change in position being due to the travel of the cam roll 102 along the cam slot 104 of the slide member 106 while the latter is held down in the position of Fig. 9 against the tension of the spring 108. As shown, the slide or cam 106 is guided on the frame member 55 by guideways 110 (Fig. 13) into which project the operative ends of a pair of levers 112 both fixed to a pivot

member 114 rotatably mounted in said frame member 55. This pivot member 114 has secured thereto a lever arm 116 (Fig. 10) which is adapted to be contacted by a cam roll 118 (Figs. 9, 10, 11, 20) fixedly carried by the head 27, it being understood in this connection that the pivot member 114 with its lever arm 116 is located substantially above the level of the lower mold member 24 (Fig. 9) or 140 (Fig. 20). When the head 27 swings forwardly to a position where the upper mold member 26 is directly above the lower mold member 24, the cam roll 118 is directly above the lever arm 116 in its slanting position shown in Fig. 10. Hence, straight-line downward movement of the head 27 will cause the cam roll 118 to contact the lever arm 116 and move it from dotted to dash line position (Fig. 10) thus providing means for holding the slide 106 (Figs. 9 and 13) in its lowermost position by reason of the swinging movement of the lever arms 112 located on the same pivoted member 114 as the lever arm 116. It follows that, during downward movement of the carrier 50, the latter is swung to the left in Figs. 1, 9 and 20 to bring the positioning member 40 and the holdown 42 into the space between the upper mold member 26 and the lower mold member 24. Conversely movement of the carrier 50 in an upward direction will be accompanied by a quick swinging movement of the carrier 50 to the right about its pintle 52 by reason of the travel of the cam roll 102 in the cam slot 104. Since the slide member 106 with the cam groove 104 is in its down position at the time the treadle 36 is released and the carrier 50 starts upwardly with its positioning member 40 and holdown 42, the latter are swung rapidly to the right (Figs. 9 and 20) at the very beginning of their upward movement thereby withdrawing members 40 and 42 laterally, i. e., in a direction lengthwise of the insole 34, from the positions shown in Fig. 9, so that the assembled parts of the insole will not be disturbed as they would be by a direct upward movement of the members 40, 42. It will be noted that, in Fig. 9, there is a slight space between the roll 102 and that part of the cam wall of 106 directly above and to the left of the said roll 102. Hence upon releasing the treadle 36 and the rod 82, the carrier 50 will jump upwardly the slight distance thus permitted so as to release some of the pressure of the members 40, 42 upon the work pieces thereby lessening the drag of these members on the work as they are withdrawn in the manner described.

Means is provided in connection with the cam member 106 to serve as a safety device for the holdown 40 and positioning member 42 in case the press should be improperly operated, e. g., through initiating a press operation while the said members 40, 42 are in the position shown at the left in Fig. 1. To this end, there is provided a cam member 119, on the swinging press head 27, which is arranged to engage a roll 121 secured to the cam member 106 to depress the latter during the forward swinging movement of the head 27, downward movement of the cam member 106 having the effect of withdrawing the holdown and positioning members 40, 42 through travel of the cam 102 along the cam path 104 during such downward movement of the member 106. Substantially at the time that the cam member 119 passes beyond the roll 121 at the end of the forward swing of the head 27, the roll 118, operative during downward movement of the said head 27, contacts the arm 116 to continue the depression of the cam member

106, thereby insuring that the members 40, 42 are withdrawn, and held in withdrawn position, out of the path of the upper mold member 26 (Fig. 1) or 142 (Fig. 20).

Whereas the insole parts 34, 38 and 44 are assembled in Figs. 9 and 9a in such manner that the steel shank 38 and the reinforcing member 44 are applied to the inner or foot-facing side of the insole, it is common to apply the shank and reinforcing members to the outer or out-sole-facing side of the insole, so much so that this latter method is usually spoken of as the "regular" Unishank work or method. To assemble the parts in the "regular" manner, the machine is provided (as shown in Figs. 1 and 20) with a lower mold member 140 of wood or other substantially unyielding material, it being understood that the upper surface of the mold member 140 is smooth and that it corresponds in curvature to that of the bottom of the last upon which the shoe embodying the insole is to be made or is curved more or less in excess of that of the last bottom to provide for over-molding of the insole unit. For cooperation with the wooden mold member 140 there is carried by the head 27 a yielding mold member or pad 142 which is made of rubber.

In order that the rear end of the pad 142 may be adjustable with respect to the wooden mold member 140 there is provided, above the pad 142 at its rear end, a bendable elastic metal member 144 above which is an eccentric member 146 secured to a stub shaft 148 which has affixed thereto a handle 150. Upon rotating the handle 150, the eccentric 146 is caused to bend the metal member 144 and also the rear portion of the pad 142 in a downward direction thereby adjusting the pad to the wooden mold member 140. Associated with the lower mold member 140 is the work supporting member 28 which carries the toe gage 30 and the toe gripper members 32 which, in the other embodiment of the invention (Fig. 9) are also carried upon the work support 28.

In assembling the parts of a Unishank insole upon the mold member 140 and work support 28, an insole member 34 is placed upon the said mold member 140 and work support 28 while the grippers 32 are in upper or work receiving position. The grippers 32 are caused to engage the toe end of the insole member 34 (to clamp the same against the work support 28) through connections to the treadle member 36 as in the construction shown in Fig. 9. Subsequently, the steel shank is placed upon the upwardly facing surface of the insole member 34 after the positioning gage 40 has been lowered into contact therewith by the same movement of the treadle which effected operation of the grippers 32. Then, by a further downward movement of the treadle, the holdown 42 is brought into operation to hold the shank member in place while the reinforced member 44 is being placed over the shank member. Upon starting the molding operation a spring pressed plunger 160 (Figs. 9 and 20), yieldingly mounted in the upper mold member 26 or 142 and its supporting structure, engages the reinforcing member 44 of the assembled insole in advance of the upper mold member to hold the parts in assembled relation while the positioning member 40 and the holdown 42 are being withdrawn to the right in Fig. 20, just as they were withdrawn to the right in the construction shown in Fig. 9.

As heretofore stated, depression of the treadle

36 has, as its first effect, the bringing of the gripper members 32 into operation whereby the insole member 34 is clamped in position against the toe gage 30. As shown in Figs. 11 and 18, the gripper members 32 are secured to a rod 170 mounted for rotation in a bearing 172 integral with a plate 173 and a block 174 both slideable on the work supporting structure 28. Secured to one end of the rotary rod 170 is an arm 175 having at its free end a roller 176 yieldingly pressed by spring 177 into contact with the upper surface of a vertically movable member 178 carried at the upper end of a vertically slideable rod 180 (Fig. 12) mounted in bearings in the machine frame. Pivoted to the slideable rod 180 is a link 184 having its other end pivoted to arm 186 secured to a short rotary shaft 188 mounted in a bearing on the machine frame, said shaft 188 having at its other end an arm 190 having at its free end a roll 192 adapted to contact a cam surface 194 near the lower end of a cam unit 195 secured to the lower end of the connecting rod 82 (Figs. 9, 10, 13, 20) and to the upper end of a piston rod 196. Upon downward movement of the piston rod 196, the roller 192 is contacted by the cam 194 and forced over to the left to the position shown in Fig. 12. This movement of the roller 192 and of the lever arm 190 is accompanied by upward movement of the lever arm 186 and hence of the vertically movable rod 180, the latter carrying at its upper end the movable member 178, such upward movement lifting the roll 176 and rotating the bar 170 to bring the gripper members 32 into contact with the insole member 34. As before stated, further downward movement of the rod 82 and of the piston rod 196 through operation of the treadle 36, results in bringing down the positioning member 40 and the holdown 42.

40 When the operator releases the treadle 36 so that the latter two members 40 and 42 may be retracted from the path of the movable mold member, as in Fig. 20, the gripper members 32 would also be released if means were not provided to hold them in operative position until the molding operation has been completed. The means referred to above comprises a locking means as shown in Fig. 12 wherein a locking member 200 is shown holding the lever arm 190 to the left although the cam surface 194 has moved upwardly away from the roller 192. This locking member 200 is carried by a lever 202 pivoted about an axis 204, a spring 206 being operative to move the locking member 200 to locking position determined by a set screw 208 carried by an upwardly extending arm 210 integral with a bracket 211 secured to the frame of the machine. As shown, the locking member 200 is moved to inoperative position by means of an abutment 212 on a surface part of a post 214 which carries the mold head 21. During upward movement of the post 214, the said abutment 212 catches the lip of a pawl 216 pivoted to the free end of the lever 202, whereby the locking member 200 is moved downwardly to unlocking position with the result that the rod 180 with the supporting surface 178 is at once projected downwardly by a spring 218. As soon as the supporting surface 178 is withdrawn, the rotatable bar 170 is moved by the spring 177 to lift the grippers 32. By keeping the grippers in operation until the molding operation is well started or even completed, there is obviated any likelihood of the sole member 34 being shifted during the molding operation and particularly

when the upper mold first contacts the assembled sole members, it being obvious from inspection of Figs. 9 and 20 that some lengthwise shifting of the sole member 34 might take place, particularly at the beginning of the molding operation, due in part to the yielding mold member and possibly also to an initial bridging effect of a more or less flat insole, if it were not for the gripper members 32. Means is conveniently provided to unlatch the locking member 200 in case it is desired to reset all the sole parts before a molding operation, the said means comprising a member 217 (Figs. 11 and 12) normally in contact with the upper surface of the latch 200 when the latter is in operative position (as shown), said member 217 being rigid with a hand lever 217a (Fig. 11) which may be depressed to trip the latch 200.

For positioning the insole 34 on the lower mold member in directions transverse of the latter, there are provided side gage members 220 (Fig. 11) each pivotally mounted at 222 and held together by a spring 224, said gage members each having an arm 226 provided at its end with a segmental rack so arranged that the racks mesh with each other thereby insuring that movement of one gage member 220 is accompanied by movement of the other gage member to the same extent but in the opposite direction. A similar pair of side gage members 230 mounted at the ends of pivoted arms 232 substantially longer than the arms which carry the gage members 220 are provided to gage the insole member 34 near the middle of the length thereof. These gage members 220, 230 are mounted upon a vertically movable rod or post 240 (Figs. 9, 10 and 20) which is spring pressed in the upward direction by a spring 241, the arrangement being such that the gage members 220, 230 are moved downwardly ahead of the upper mold member, returning to gaging position subsequently to the upward movement of said mold member, as will now be described.

As shown in Figs. 9 and 10, there is connected to the lower end of the rod 240, by means of a block 242 pivoted on the rod, a lever 243 engaging said block and secured to a short shaft 245 journaled in a bearing supported by a bracket secured to the machine frame, the said shaft 245 having also secured thereto a lever arm 247 having surfaces arranged to be contacted by a roller 249 carried in the upper end of an arm 251 rigidly secured to the lower end of the post 214 which carries at its upper end the mold member head 27. Upon downward movement of the post 214, the roller 249 contacts the upper surface of the lever 247 near the end thereof and thereby moves the rod 240 downwardly with the result that the side gage members 220, 230 are moved downwardly just in advance of the upper mold member. At the extreme downward position of the roller 249, the latter is contacting the inclined end of the lever 247 whereby the gage members and the rod 240 are held in lowest position. During the downward movement of the rod 240, a latch member 253 pivoted at 255 is swung downwardly by a spring 257, the arrangement being such that an end 259 of the latch member 253 engages behind an abutment 261 movable with the member arm 247 to hold the latter locked in a downward position. Hence, the side gage members 220, 230 are also locked in a position below the upper surface of the lower mold member thereby facilitating the work of an ejector member 250 in 75

discharging the molded sole forwardly from the field of molding operations. It is only when the roller 249 has moved upwardly with the post 214 and the mold carrying head 27 far enough to disengage the latch member 253 from the abutment 261 that the gage carrying post 240 is freed to be projected upwardly by the spring 241. This means that the gage members 220, 230 are returned at the proper time for positioning operations upon a succeeding piece of work. For a more complete disclosure of the construction and arrangement of these side gage members reference should be had to United States Letters Patent No. 2,023,583, granted June 15, 1937, upon application of J. M. Whelton.

Upon upward movement of the upper mold member 26 or 142, it is desirable to eject the molded shoe part, there being provided for this purpose an ejector mechanism comprising the two-pronged ejector member 250 (Figs. 9, 10, 11 and 16), the said member being secured to a slide bar 252 horizontally slidable in a guideway 254 stationary in the main frame of the machine. Pivoted to the slide member 252 is a link 256 also pivoted to the upper end of a lever 258 integral with a sleeve 260 (Fig. 16) rotatable on a short shaft 262 mounted in the machine frame. Also extending from said sleeve 260 is an arm having a hook 264, a spring 266 connected to said hooked arm being provided to return the lever 258 and the ejector members 250, 252 to the inoperative or retracted position shown in Figs. 10 and 16. Pivoted upon the post 214 (which carries the mold head 27) is a hook or pawl member 270 arranged to engage the hooked arm 264 upon upward movement of the upper mold carrying member 27, the result being that the ejector member 250 is projected instantaneously to the left in Fig. 10, that is, in a direction toward the front of the machine in Figs. 9 and 11 to eject the molded shoe part in a forward direction immediately after the molding operation.

Since the upper surface of the lower mold member is not a plane surface, the shoe part should be lifted somewhat from the lower mold member to a position where it may be readily ejected laterally, that is, toward the front of the machine. For this purpose there is provided a plunger member 283 (Fig. 20) in line with the upper spring pressed plunger 160 (Fig. 20), the arrangement being such that the two plungers cooperate to hold the molded shoe part for ejection by the ejector member 250. As shown, the plunger member 280 is carried at the upper end of a rod 282 (Fig. 10) pivoted at its lower end to an arm 284 in turn pivoted at 286 to a part of the machine frame. Pivoted on the arm 284 is a member 292 normally held against a stop 294 on said arm by a spring 296. Upon downward movement of the post 214 with its mold carrying head 27, a cam member 298 secured to said post wipes by the pivoted member 292 which subsequently springs back into position above the projecting portion of said cam member 298. However, upon upward movement of the post 214, the cam member 298 contacts the free end of the pivoted member 292 and shoves the latter and the pivoted member 284 over to the left (Fig. 10) about the pivot 286, swinging of the arm 284 about the pivot 286 causing the plunger 280, 282, to be projected upwardly carrying with it the molded shoe part and also the spring pressed plunger 160 which is in contact with the opposite side of the shoe part. The timing is such that the ejector member 250 strikes the molded shoe part just as the

upper plunger 160 is releasing it due to upward movement of said plunger with the upper mold member 27.

Upon reference to Fig. 1 of the drawings it will be observed that there are two presses or molding machines and that, while one is operating to mold a shoe part, the other is in open or work receiving position with the upper mold member 26 (or 142, Fig. 20) and the head 27 displaced backwardly, as shown in full lines in Fig. 10, thus facilitating the work of the operator in assembling shoe parts upon the lower mold member 24 (or 140, Fig. 20). As already pointed out, each mold head 27 is carried by a post 214 which is arranged to be swung forwardly to bring the upper mold directly above the lower mold member, the said post 214 being then moved downwardly to effect the molding operation. Preferably, and as shown, hydraulic means is provided for effecting the up-and-down movements of the post 214 and of the mold head 27.

Upon reference to Figs. 2, 3, 4 and 9, it will be seen that the lower end of the post 214 has fastened thereto a pivot pin 301 upon which is pivoted a block 303 to which is fastened a piston rod 305 having secured thereto between its ends a small piston 307 (Figs. 2 and 4) movable in a small cylinder 309, said piston rod 305 also having secured thereto at the lower end thereof a second piston 311 much larger than piston 307 and movable in a piston cylinder 313. It is to be understood that the hydraulic means for operating one mold head 27 is identical with that for operating the other mold head and hence that there are two sets of pistons and piston cylinders in the arrangement already described and as shown in Fig. 4. Pivoted at 315 (Fig. 3) in the upper end of a stationary post 317 is a lever 319 having its opposite ends forked at 321 to straddle the upper ends of the respective piston rods 305 and engage under the blocks 303, the arrangement being such that, upon downward movement of one piston rod 305 due to the application of hydraulic pressure, the other piston rod 305 will be lifted upwardly to its position of rest by the lever 319.

When it is desired to initiate a pressure applying operation, the operator depresses one of a pair of latch releasing members 325 (Fig. 1) each carried at the upper end of a rod 327 (Figs. 1 and 3) vertically movable in a bearing in a cover plate 329, said rod having its lower end pivoted to a bell crank lever 331 rocking about a pivot in the machine frame, the other end of each bell crank lever 331 being pivoted to the adjacent end of a rod 333 extending in a substantially horizontal direction between said bell crank levers 331. Between its two ends the rod 333 passes through openings in a pair of latch members 335 (Fig. 3) and has secured to its intermediate portion a pair of blocks 337 each adapted to engage the inner upright surface of the corresponding latch member 335, each of the latter having at its upper end an inturned finger portion adapted to engage in a notch 339 to lock a rotary member 341 against rotation. However, upon downward movement of a latch releasing member 325 (Fig. 1) the bell crank 331 is operated to move the rod 333 to withdraw one of the latch members 335 from its cooperating notch in a member 341. In Fig. 3 the right-hand releasing member 325 (Fig. 1) has been depressed, thus removing the right-hand latch 335 from the corresponding notch 339 and the rotary member 341 has been rotated along with

a valve (hereinafter disclosed) to initiate a pressure applying operation, as will be hereinafter described. It will be observed in Fig. 3 that the finger end of the latch member 335 rests on the cylindrical surface of the rotary member 341 ready to drop again into the notch 339. A spring (not shown) is provided for holding the latch members 335 yielding toward latching position with respect to the rotary member 341 so that the operator must hold the latch releasing member 325 in depressed latch-releasing position while he swings a lever 345 (Figs. 1, 2 and 3) to initiate a pressure applying operation. The lever 345 is fastened on a stub shaft 345a, rotatable in a bearing in the machine frame, to the other end of which is fastened a lever arm 345b connected by a link 345c to a lever arm 345d rigidly attached to a shaft 347. To effect a pressure applying operation, the handle 345 is connected in the manner just described to a rotary valve member fixed to shaft 347 of member 341 and located in a valve housing 351 (Fig. 5), the valve therein being preferably of the type shown in Fig. 6 of United States Letters Patent No. 2,231,963, granted February 18, 1941, on an application filed in the name of Frank E. Stratton.

Within the housing 351 there is a chamber (containing the valve member mentioned above) into which open a number of pipes of which pipes 353 (Fig. 3) carry fluid under pressure to the upper ends of the small cylinders 309 (Figs. 3 and 4), it being understood in this connection that said valve member in the valve housing 351 is operative to connect only one of the pipes 353 at a time with a pressure pipe from a pump indicated in general at 355 (Fig. 4). From this pump 355 there leads upwardly a pressure pipe 357 which ends in the housing or valve chamber 351 (Fig. 3), the pump chamber having also connected thereto a supply pipe 359, the lower end of which dips into a reservoir 361 of pressure fluid. Connected to the valve housing or chamber 351 is a pipe 363 which serves as an exhaust pipe for returning pressure fluid to the reservoir 361.

Upon turning the handle 345 to the right, as in Fig. 1, fluid pressure medium from the pressure pipe 357 is directed in the valve chamber 351 to one of the pipes 353 and thence to the upper end of one of the smaller cylinders 309 whereby the corresponding pistons 307 and 311 are forced downwardly to move the upper mold head in its operative stroke. During the first part of the downward movement of the piston 311, liquid is drawn into the large cylinder 313 by suction through a pipe 365 (Fig. 2), the lower end of which is well below the level of the pressure fluid in the reservoir 361. At a certain point in the downward movement of the pistons 307, 311, a valve 367 (Fig. 2) is forced back by the pressure medium under high pressure in the small cylinder 309 against a spring 371 so that pressure is communicated instantly to the pressure medium already collected in the large cylinder 313, whereby heavier pressure is applied to the movable parts because of the larger area of the large piston 311. The mold pressure is maintained in the selected press or molding machine so long as the handle 345 and the valve controlled thereby remain in the position shown in Figs. 1 and 3. Upon throwing the handle 345 over to the left in Fig. 1, pressure is removed from the right-hand set of pistons and piston cylinders to the left-hand set with the result that a molding operation begins with the left

press while the corresponding parts in the right press are restored to open work receiving position by the lever 319, as before described. For a more complete description of the operation of the hydraulic mechanism for selectively operating the twin presses or molding machines, reference should be had to the Stratton patent mentioned above.

As heretofore stated, the gripper members 32 together with the work positioning member 40 and holdown 42 are moved downwardly into work engaging position by means of rod connections 82 and 194 to a piston rod 196. A piston rod is employed instead of a direct connection to a treadle mechanism inasmuch as it is desirable to operate the work holding and positioning members associated with each molding unit from one treadle mechanism. This can be readily accomplished by providing fluid operated means for effecting operation of such work holding and positioning members under control of a single treadle. Upon reference to Figs. 2 to 8, inclusive, of the drawings it will be found that the said fluid operated means comprises a control valve device 303 (Figs. 2 and 3) operated by direct connections to the treadle 36. Extending from the control valve 303 are pipes leading to a set of rotary valves 302 under control of the operator through the hand lever 345 by which each molding press in turn is caused to operate upon proper manipulation of the said lever. The said rotary valves control the application of fluid under pressure alternately to relatively small cylinders 314, 316 for operating alternately the piston rods 196 which effect operation of the work holding and positioning members as already described.

Upon inspection of Figs. 2 and 3 it will be seen that the control valve 303 comprises a cylinder 318 in which slides a piston rod 320 supported by a spring 320a (Figs. 2 and 4) and having spaced piston heads 322, 324, the space between the heads 322, 324 being, under certain conditions, filled with fluid under pressure entering from a pipe 328. As shown in Figs. 2 and 4, the spring 320a is supported at its ends against buckling and other displacement by studs or pins projecting into the spring. If now the treadle 36 be depressed a suitable distance, the piston rod 320 is moved downwardly (through suitable connections hereinafter described) and fluid under pressure is admitted to a pipe 328 (Fig. 3), a further depression of the treadle having an effect of directing the pressure fluid also into a second pipe 330, the pressure fluid from these two pipes 328, 330 being directed to effect two successive downward movements of the piston rod 196 alternately in one or the other of the cylinders 314, 316, as will hereinafter be described. If now, the treadle be released for upward movement by spring 31, the piston rod 320 will move upwardly, under action of the spring 320a, and thus pipes 328 and 330 will be successively connected with an exhaust pipe 332 (Fig. 3). If only pipe 330 be thus connected, the holdown member 42 will be released to permit adjustment of the steel shank piece 33. If pipe 328 be also connected to the exhaust, member 40 will also be released to permit repositioning of the parts of the assembled work pieces.

For connecting the piston rod 320 (Figs. 2 and 3) of the valve cylinder 318 with the treadle 36, the said piston rod 320, which extends a substantial distance below the cylinder 318, has fixedly secured thereto a collar 336, the latter be-

ing normally in the path of a finger 338 extending laterally from a clamp member 340 secured to the upper end of a rod 342 whose lower end is pivoted to the treadle 36. Since the rod 342 passes through the reservoir 361 for the pressure medium, it is surrounded by a tube 346 the upper end of which extends substantially above the level of the pressure medium, the said tube 346 being of a diameter to permit necessary movements of the rod 342. It will be clear that, upon downward movement of the treadle 36, the finger 338 on the clamp member 340 will engage the collar 336 on the piston rod 320 to effect movement of the latter downwardly against the resistance of the spring 320a, as above described. As shown in Fig. 3, the clamp member 340 at the upper end of the rod 342 fixedly holds a pin 348 which passes through a slot in an ear 350 extending laterally from the wall of the cylinder 318 at the lower end thereof, the purpose of the pin and slot being to guide the upper end of the rod 342 in certain movements of the latter, particularly while it is being moved into and out of operative relation to the piston rod 320, a spring 349 being provided near its upper end to return said rod 342 to its normal position.

It is considered desirable to provide means for disconnecting the treadle 36 from the piston rod 320 in the valve cylinder 318 to insure upward movement of the work holding and positioning members 40, 42, at the proper time, out of the way of the descending mold member, automatically operating means being provided for this purpose. Conveniently, the disconnecting means comprises a cam member 352 (Fig. 3) extending forwardly from a plate 354 carried fixedly at the lower end of an arm 356 pinned to the pivot shaft 315 to which the double armed lever 319 is secured for rocking movement. At its opposite ends, the lever 319 is forked to straddle the upper ends of the piston rods 320 and to engage the lower surfaces of washers on the lower ends of the blocks 303 carried by the lower ends of the posts 114. Hence, as the double armed lever 319 swings first in one direction and then in the other, as first one post and then the other is pulled downwardly by a piston rod 320, the cam 352 will effect disconnection of the treadle by moving the finger 338 to one side of the collar 336 on the valve piston rod 320, thereby freeing the latter for automatic control as before mentioned.

As stated above, the pipes 328 and 330 leading from the control valve device 303 are to direct fluid under pressure to each of the cylinders 314, 316 in turn whereby the corresponding piston rod 196 is moved downwardly in two steps. Instead of having a direct connection of these pipes 328 and 330 with the cylinders 314 and 316, it is considered desirable to provide a control mechanism so that first one and then the other of the piston rods 196 is conditioned for operation at the will of the operator. Hence, the pipes 328, 330 are connected to the rotary valve control mechanism indicated in general by the reference character 302 (Figs. 2 and 5). This valve mechanism comprises rotary valve members 370, 372 (Figs. 5, 7 and 8) which move as one since they constitute an integral valve member loosely mounted on the shaft 347. Said shaft has extending transversely thereof a pin 376 the ends of which are movable in arcuate slots 378, 380 in valve member 370, while a hub portion of a large valve member 382 also has slots in which pin 376 is snugly received, the valve 382 being

mounted for rotation in the valve housing 351. It will be understood that the valve 382 in the housing 351 is pinned to the shaft 347 to be operated by the hand lever 345. The shaft 347 controls through the valve member 382 the pressure medium of operating both the small pistons 307 (Figs. 3 and 4) and also the large pistons 311 in each of the cylinders 309 and 313, respectively, for causing pressure applying operations of each molding press. As already stated, the details of the large valve 382 in the housing 351 are not disclosed herein since it is preferably of the type shown in Fig. 6 of the Stratton patent mentioned above.

The pin and slot connection (376, 378 and 380) between the rotary valve 382 and the rotary valves 370, 372 is so constructed and arranged that a 45° rotation of the main valve 382 will cause no rotation of the valves 370, 372 during the first 22½° due to the arcuate slots 378, 380, the said valves 370, 372 being carried along with the main valve 382 during the second (approximately) 22½° rotation of said valve 382, whereby the valves 370, 372 are moved to a position where the fluid medium is held in one of the cylinders (314, 316) to hold down one of the piston rods 196 whereby the work positioning members on that side are held in work clamping position. Loosely mounted on the valve shaft 347 is a third rotary valve 400 loosely connected by a pin 402 to the valve 372, the pin 402 being fixed to valve 400 and having its other end projecting into an arcuate slot in the valve 372 of a size such that the described rotation of the valves 370 and 372 by the described pin and slot connection with the large valve member 382 has no effect on the valve member 400. However, when the valve member 400 is rotated through 22½° (approximately) by means hereinafter described it does so without effecting movement of the valve members 370 and 372. During the second part of its 45° movement the valve member 400 moves both of the valve members 370, 372 through the pin 402 to a position where the control valve 300 may operate selectively on either the right-hand cylinder 314 or the right-hand cylinder 316. In its 45° rotation to the right in Fig. 6, the valve 400 connects a pressure pipe 403 with the bottom end of the right cylinder 314 through a pipe 430 (Figs. 3 and 6) and at the same time connects an exhaust pipe 431 to the bottom of the left cylinder 316 through pipe 430a. During the last 22½° (approximately) of rotation of the valve 400, the valves 370, 372 are carried along by pin 402 to a position such that the pipes 422a and 428a of left-hand cylinder 316 are connected to the pressure pipes 328 and 330, respectively, leading from the control valve 300, thereby conditioning the valve cylinder 316 for downward movement of the work positioning members 40, 42 of the left-hand press unit upon subsequent depression of the treadle 36. At the same time, the pipes 422, 428 of the right cylinder 314 are connected to the exhaust pipe 431a (Figs. 5, 7, 8) since the pipe 430 is connected to the pressure pipe 403 (Fig. 6) to return the work positioning member 40, 42 of the right press unit to their upper position of rest. As stated, the valve member 400 connects the pressure pipe 403 to the bottom of the right-hand cylinder 314, the purpose being to expedite upward movement of the members 40, 42 (springs 61, 76 and 108 also tending at all times to lift the said members 40 and 42) and to

hold the said members in their upper positions of rest.

Upon reference to Fig. 3 of the drawings it will be seen that the lower end of the piston rod 196 is receivable in the valve cylinder 314 (or 316) and that there is attached to said rod 196 within the cylinder 314 a piston head 440. Surrounding the rod 196 above the head 440 is a sleeve 442 having a collar 444 rigid therewith to engage the head 440 to force downwardly the piston rod 196 when pressure is applied through the pipe 422, downward movement of the sleeve 442 being limited by a stop member 446 secured to the sleeve and adapted to engage a surface 448 at the upper end of the valve housing. The downward movement caused by pressure medium entering from the pipe 422 and acting on the sleeve collar 444 is the first step in the downward movement of the rod 196, such downward movement of the rod 196 having the effect of bringing a second head 450 on the piston rod 196 below the inlet of the pipe 422 so that a second step in the downward movement of said piston rod 196 is effected upon directing pressure medium under pressure through the pipe 422 upon the continued downward movement of the treadle 36, this second downward movement of the rod 196 having the effect of bringing down the holdown 42 upon the steel shank piece as before described. There is at the lower end of the valve cylinder 314 an opening into the third pipe 430 which may be connected either to an exhaust pipe 431 (Fig. 6) or to the pressure pipe 403 for lifting the piston rod 196 to its upper position and maintaining it there with the work positioning members 40, 42 in their upper position of rest. It will be understood of course that the description of valve cylinder 314 and the piston 196 applies equally well to the valve cylinder 316.

Automatic means is preferably provided for alternately conditioning the piston cylinders 314 and 316 for operation by the treadle through the control valve 300, thus facilitating the operation of assembling a work piece with the aid of the work positioning and holding members 32, 40 and 42, said automatic means also operating to cause the piston in the other piston cylinder to return to its upper position whereby movement of said work positioning and holding members to retracted position out of the path of the descending mold member is assured. Said automatic means comprises a cam roll 500 (Fig. 3) secured to the right-hand end of the lever 319 which, on the downward movement of said end of the lever, contacts the cam surface 502 secured adjustably to a lever 504 pivoted at 506 to the end of a bracket 508 extending from a stationary part of the machine frame. Contact of the roll 500 with the cam 502 moves the lever 504 to the right about its center 506, thereby causing a rotary movement of the valve member 400 through a link connection 510 with a lever arm 512 secured to said valve member 400 (Figs. 3, 5 and 6). This movement of the valve member 400 to the right into the position shown in Figs. 3 and 6 results in connecting the bottom end of the right-hand piston cylinder 314 to the pressure pipe 403, and in connecting at the same time, the lower end of the left-hand piston cylinder 316 to an exhaust pipe, as already described. In the latter case, the conditions are rendered appropriate for bringing the left-hand set of work positioning members successively into operative position through proper operation of

the treadle 36. It is to be noted in this connection that downward movement of the right mold member is accompanied by downward movement of the right end of the double-arm lever 319 and the consequent operation of the cam roll 500 upon the cam 502 to effect the described movement of the valve member 400 to the right in Figs. 3 and 6, one consequence of said movement of the valve member 400 being the prompt return of the holdown and positioning members (associated with the right-hand mold members) to their upper positions of rest.

Upon upward movement of the right lever arm 319 in Fig. 3, the cam roll 500 will contact a cam surface 514 also carried adjustably by the lever 504 whereby said lever will be swung over to the left in Fig. 3 about its pivot 506, to cause movement of the valve 400 in a counterclockwise direction in Figs. 3 and 6, thereby to bring said valve member 400 into a position such as to cause the application of pressure to the bottom end of the left-hand piston cylinder 316 through the pipe 430a and at the same time cause movement of the valves 370 and 372 to exhaust or release the pressure in the top part of the same cylinder 316, whereby the work positioning members 40, 42 are retracted out of the path of the descending mold member on the left side of the twin machine. At the same time, the valve cylinder and other parts connected operatively thereto are conditioned for operation to bring down the right-hand work positioning members upon proper operation of the treadle 36.

To assist the operator in locating the toe gage 30 in connection with sole members of different sizes and styles of shoes, there is provided special means including size and style scales for securing the desired adjustment of said gage 30. As shown most clearly in Figs. 9 and 17 to 19, inclusive, the work supporting member 28 is provided with a work supporting table 520 upon which rests the plate 173 having integral therewith the toe gage 30. Also integral with the plate 173 is the block 174 which is slidably supported in a slot in the rear end of the table 520 and in a dovetail formation 522 (Figs. 17 to 19 inclusive). When it is desired to adjust the gage 30, a set screw 524 is loosened to free a gib 526 (Fig. 19) and also the block 174 so that the latter may be adjusted along the slot in the table 520. Extending downwardly from the block 174 below the table 520 is an arm 530 to the lower end of which is rigidly fastened a lengthy bar 531 (Fig. 1) also rigidly fastened to the arm 530 of the toe gage mechanism of the other press unit so that adjustment of the toe gage mechanism at the left in Fig. 1 is accompanied by the same adjustment of the gage parts at the right in Fig. 1. At a point intermediate the ends of arm 530 (Fig. 9), there is pivoted thereto a link 532, the other end of the link being pivoted at 534 to an arm 536 mounted rotatably on a fulcrum pin 538 supported by a side wall of the work support 28. Pivoted to the arm 536, at a point intermediate its ends, by a pin 540 is a link 542 the other end of which carries a connecting pin 544 movable in a slot 546 in a sector-shaped lever 548, the said connecting pin 544 being provided with a knurled head so that it may be readily rotated to loosen or tighten the pin in the said slot 546 in carrying out adjustment of the link 542 lengthwise of said slot 546. Extending from the last-mentioned end of the link 543 is a pointer or indicator 550 movable over a regulatory scale 552. As shown, the lever

548 is pivotally mounted at 554 in the upper end of a bracket 556, the sector-shaped lever 548 having on its curved upper edge a rack or toothed formation 558 having in mesh therewith teeth 560 on a rotary adjusting member 560. As shown, the member 560 is rotatable on a pin 562 (Fig. 17) after it has been pulled to the left by means of a finger member 563 against the pressure of a spring 564, the purpose of such movement of the member 560 being to free it from engagement with a stationary tooth surface 566 so that it may be rotated to cause movement of the lever 548 about its pivot point 554. After rotating the lever 548 to the desired amount, the latter is locked in its adjusted position upon releasing the regulating member 560 which is at once moved back into engagement with the toothed surface 566, it being obvious that locking of the regulating member 560 by the stationary toothed surface 566 results also in locking the lever 548 since the member 560 is constantly in mesh with the rack 558 on the lever 548. Movement of the lever 548 is transmitted to the arm 536 through the link 542 and movement of the arm 536 causes movement of the block 174 through the link connection 532. Movement of the lever 548 is guided as to its amount by a stationary pointer 570 in connection with a size scale 572 on the exposed surface of the sector-shaped lever 548. By this means the block 174 and hence the toe gage 30 are adjusted on the work supporting table 520 various selected distances, as indicated by the size scale 572. For greater accuracy it is often necessary or desirable to get a finer adjustment for size by adjustment of the pointer 550 over the regulatory scale 552, it being obvious that the further pointer 550 is moved away from the fulcrum pin 554 the greater will be the movement transmitted by the lever 548 to the block 174 through the link 542. As a further refinement, there is provided on the surface of the table 520 a style scale, indicated in general by the reference character 574 (Fig. 18). It will be clear from a comparison of Figs. 9 and 20 that the work support 28 with all of the means just described to adjust the toe gage 30 thereon is the same in both of the illustrated constructions and that the said work support 28 has been lifted up into the position shown in Fig. 9 by introducing a spacing block 580, the latter being used when shoe sole parts of the so-called "reverse" arrangement are to be assembled for a molding operation, whereas in Fig. 20 the spacing block 580 is removed so that the work support 28 may be positioned as shown in said Fig. 20 for "regular" work. For a complete disclosure of the method of utilizing the size scale (including the regulatory scale) and the style scale, reference should be had to United States Letters Patent No. 2,119,564, granted June 7, 1938, on an application filed in the name of J. M. Whelton.

Assuming that the right upper mold member is in its upper position of rest, as indicated in Fig. 9, and that the operator is about to begin assembling of the sole parts, the piston 196 being in its raised position as in Fig. 3, the operator depresses the treadle 36 far enough to direct pressure medium from the pressure pipe 326 (Figs. 2 and 3) to the pipe 422 (Fig. 3), the pressure medium passing by way of pipe 328 and then through the rotary control valve device 302 to the pipe 422 and entering near the top of the valve cylinder 314 to effect the first downward movement of the piston rod 196, whereby the grippers 32 are caused to engage the toe end of an insole which the oper-

ator has placed against the toe gage 30, the same downward movement of the piston rod 196 having also the effect of bringing down also the positioning member 40 which engages the upper surface of said sole member to serve as a positioning member for the steel shank piece 38 and also as a holdown for the sole. After the steel shank piece has been positioned with the aid of the positioning member 40, the operator continues the depression of the treadle 36 in the same direction whereby pressure medium passes through the pipe 330 from the control valve 300 and through the rotary control valve mechanism 302 to the pipe 428 (Fig. 3), thereby causing a second downward movement of the piston rod 196 to bring down the holdown 42 on top of the shank piece 38. The reinforcing member 44 is then placed on top of the shank stiffener 38. If now the operator is satisfied with the positioning of the shoe parts, he may initiate a molding operation on the assembled shoe part by depressing the handle 325 on that side of the twin machine and, while holding it depressed, then throw the handle 345 to that side, thus causing the upper mold member 26 (or 142) to descend into cooperative relation with respect to the lower mold member. During descent of the upper mold member the plunger holdown 160 engages the assembled work piece substantially in advance of the descending mold member to hold the parts properly assembled while the positioning members 40, 42 are being withdrawn from the position shown in Fig. 9 to that shown in Fig. 20. If the operator releases the treadle 36 at about the time the plunger holdown 160 engages the assembled work piece, the piston 196 on that side of the twin machine immediately moves upwardly to effect upward movement of said work positioning members 40, 42, the movement of the piston 196 under hydraulic pressure supplementing the action of the springs 73 and 108 in moving said members 40, 42 to their upper positions of rest. If the operator does not release the treadle 36 at exactly the right time, it is not a matter of much importance since the treadle is disconnected from the control valve 300 by means of the automatically operated cam 352 on the lever arm 356, the latter receiving its movement through direct connections with the double arm lever or walking beam 319. Upon being released from the treadle 36, the valve piston 320 in the control valve 300 is moved upwardly promptly through expansion of the spring 320a such upward movement of the piston 320 resulting in a similar upward movement of the piston plunger 196, the latter operating through direct connections to effect upward movement of the work positioning members 40 and 42. Because of the cam arrangement, including the cam member 106 (Figs. 9, 13 and 20), the positioning members 40, 42 are withdrawn initially in a largely lateral direction and then upwardly to their positions of rest. Substantially at the end of the upward movement of the upper mold member, the grippers 32 are released through automatic tripping of the latch member 200 (Fig. 12).

If, after assembling the shoe parts with the aid of the positioning and holding members 32, 40 and 42, the operator should decide to readjust some or all of such parts he may readily do so. This is accomplished by permitting the treadle 36 to rise under action of the spring 37, thus releasing the piston rod 320 to the action of the spring 320a, whereby the pressure medium in the pipe 330 and in the pipe 428 is directed to the ex-

haust through pipe 332, thereby permitting an upward movement of the piston rod 196 (under action of the spring 76) to an extent such as to release the holdown 42, thus enabling the operator to reposition the steel shank piece 38. If it be considered necessary to reposition the sole member 34, the treadle 36 may be allowed to rise still further to connect the pipes 328 and 422 to the exhaust, thus permitting a further upward movement of the piston rod 196 by spring 76, whereby the member 40 is lifted. Then, upon depressing the manually operable member 217 (Fig. 12) the latch 200 is depressed, thereby effecting release of the grippers 32 so that the sole member 34 may be repositioned.

While one shoe part is undergoing a molding operation the operator will assemble the parts of another shoe part on the lower mold member of the other press or molding machine. Upon initiating a molding operation in connection with this second machine or press, there is initiated also the return of the first-mentioned molding machine or press to its work receiving position with the upper mold member back in the full line position shown in Fig. 10 and with the work positioning and holding members 32, 40, and 42 in the work receiving position shown at the left in Fig. 1.

Having described my invention, what I claim as new and desire to secure by Letters Patent of the United States is:

1. In a machine for assembling and operating upon shoe parts, a gage member against which a shoe part is located, a gripper member to hold said shoe part against the gage member while it is being operated upon, means for locating another shoe part with respect to the first-mentioned shoe part, and means under control of the operator to operate said gripper member and subsequently said locating means, whereby the first-mentioned shoe part is held in proper position against the gage member while a second shoe part member is being assembled thereon.

2. In a machine for assembling and operating upon shoe parts a gage member against which a shoe part is located, a gripper member to hold said shoe part against the gage member while it is being operated upon, means for operating the gripper member to holding position, means for locating a second shoe part member on top of the first-mentioned shoe part member, means for operating said locating means into and out of operative position, a single manually operable member having connections to both said operating means to provide for their operation in succession, and means for locking the gripper member in work holding position while the shoe part locating means is moved out of operative position.

3. In a machine for assembling and operating upon shoe parts, a gage member against which a shoe part is located, a gripper member to hold said shoe part against the gage member while it is being operated upon, means for holding a second shoe part on top of the first-mentioned shoe part, fluid operated means for moving said holding means and said gripper member to their operative positions, and a single manually operable member to effect operation of said fluid operated means to move the gripper member and the holding means one after the other in time determined by the operator.

4. In a machine for assembling and operating upon shoe parts, a gage member against which a shoe part is located, a gripper member to hold said shoe part against the gage member while it is

being operated upon, a holddown member for holding a second shoe part on top of the first-mentioned shoe part, fluid operated means for moving said holddown member and said gripper member to their operative positions, a control valve for said fluid operated means, and a manually operable member operating through said control valve to effect operation first of the gripper member and secondly of said holddown member upon successive movements of said manually controllable member.

5. In a machine for assembling and operating upon shoe parts, a gage member against which a shoe part is located, a supporting surface for said gage member and for the shoe part located by the latter, a plurality of gripper members movable to engage the upper surface of the shoe part located against the gage member to press said shoe part firmly against the supporting surface, thereby to hold it against displacement during subsequent operations, said gripper members being located side by side and being sufficient in number to engage effectively shoe parts of a wide range in widths, and means under the control of the operator to effect movement of the gripper members into work gripping position.

6. In a machine for assembling and operating upon shoe parts, a gage member against which a shoe part is located, a supporting surface for said gage member and for the shoe part located by the latter, a gripper member movable to engage the upper surface of the shoe part located against the gage member to press said shoe part firmly against the supporting surface, thereby to hold it against displacement during subsequent operations, means under the control of the operator to effect movement of the gripper member into work gripping position, and means automatically operative to lock the gripper member against return to open work releasing position following release of said manually operable member by the operator.

7. A machine according the claim 6 in which manually operable means is provided for releasing the gripper member from the locking means.

8. In a machine for assembling and operating upon shoe parts, a gage member against which a shoe part is located, a gripper member to hold said shoe part against the gage member while it is being operated upon, a positioning member to locate a second shoe part with relation to the first-mentioned shoe part, a holddown member movable to engage the top surface of the second shoe part after it has been located by said locating member, and means including a manually controllable member to effect operation of the gripper member, the positioning member, and the holddown in succession in the order given.

9. In a machine for assembling and operating upon shoe parts, a gage member against which a shoe part is located, a gripper member to hold said shoe part against the gage member while it is being operated upon, a positioning member to locate a second shoe part with relation to the first-mentioned shoe part, a holddown member movable to engage the top surface of the second shoe part after it has been located by said locating member, fluid operated means furnishing the power to move the gripper member, the positioning member and the holddown to their operative positions, a control valve in said fluid operated means, and a manually operable member operating through said control valve to secure operation of said gripper member, locating member

and holddown successively in the order named.

10. In a shoe part assembling and molding machine, upper and lower mold members relatively movable to effect molding operations upon shoe parts assembled on the lower mold member, means for locating a shoe part on the lower mold member, a positioning member for locating a second shoe part on the first-mentioned shoe part, a holddown member arranged to engage the upper surface of the second shoe part to hold it in position against the positioning member, said positioning member and holddown being movable into the space between said mold members in moving to operative position, and means for retracting said positioning member and holddown in a substantially lateral direction at the beginning of relative approaching movement of said molding members, said means comprising cam means movable into position to effect retraction of the positioning member and holddown at the beginning of the relative approaching movement of the mold members.

11. In a shoe part assembling and molding machine, upper and lower mold members relatively movable to effect molding operations upon shoe parts assembled on the lower mold member, means for locating a shoe part on the lower mold member, a positioning member for locating a second shoe part on the first-mentioned shoe part, a holddown member arranged to engage the upper surface of the second shoe part to hold it in position against the positioning member, said positioning and holddown members being movable into the space between said mold members in moving to operative position, means for retracting said positioning and holddown members in a substantially lateral direction during relative approaching movement of the mold members, said retracting means comprising a cam member operatively connected to the holddown and positioning members, and a co-operating cam path member for the cam member, said cam path member being movable to its operative position during movement of the positioning and holddown members to their operative positions whereby retraction of said positioning member and holddown takes place promptly upon relative approaching movement of said mold members.

50 12. A machine constructed according to claim 11 in which means operated during relative approaching movement of said mold members serves to hold the cam path member in operative position during retraction of the shoe part positioning and holddown members.

13. In a machine for operating on shoe parts, a work supporting member, a member to cooperate with the first-mentioned member in performing operations on a work piece, said members being relatively movable between work receiving and work treating positions, a work positioning member movable into the path of relative movement of said members to position parts of the work piece with respect to one another on the said work supporting member, manually controlled hydraulic means to move the work positioning member to its operative position, and means automatically operative to cause said hydraulic means to retract the work positioning member toward its inoperative or rest position during relative movement of the work treating members into work treating position.

14. In a machine for operating on shoe parts, a work supporting member, a member movable to cooperate with the first-mentioned member in

performing operations on a work piece, a work positioning member movable into the path of movement of the second-mentioned member to position parts of the work piece with respect to each other on said work supporting member, manually controlled hydraulic means to move the work positioning member to its operative position, said hydraulic means being operative to move the second-mentioned member to work treating position, and means automatically operative to cause said hydraulic means to retract the work positioning member toward its inoperative or rest position during the movement of said second-mentioned member into work treating relation with respect to the work supporting member.

15. In a machine for operating on shoe parts, a work supporting member, a member to cooperate with the first-mentioned member in performing treating operations on a work piece, said members being relatively movable between work receiving and work treating positions, a work positioning member movable into the path of relative movement of said members to position parts of the work piece with respect to each other on said work supporting member, hydraulic means comprising a cylinder, a piston and a piston rod movable therein for moving the work positioning member between its operative and inoperative positions, a control valve device in the said hydraulic means, a manually operable member to condition the control valve device whereby said piston and piston rod are caused to move the work positioning member into its operative position, and means automatically operative to cause said hydraulic means to project the piston and piston rod in the reverse direction in timed relation to the relative movement of the work treating members, thereby to move the work positioning member out of the path of the relative approaching movement of work treating members.

16. In a machine for operating on shoe parts, a work supporting member, a member movable to cooperate with the first-mentioned member in work treating operations on a work piece, a work positioning member movable into the path of movement of the second-mentioned member to position parts of the work piece with respect to each other on said work supporting member, and hydraulic means including a manually controlled valve device to move the work positioning member to its operative position, said hydraulic means including a second valve device operative in timed relation to the movement of the second-mentioned member to return the work positioning member toward its inoperative or rest position during the movement of said second-mentioned member into work treating relation with respect to the work supporting member.

17. In a machine for operating on shoe parts, a work supporting member, a member to cooperate with the first-mentioned member in work treating operations on a work piece, said member being relatively movable between work receiving and work treating positions, a work positioning member movable into the path of relative movement of said members to position parts of the work piece with respect to each other on said work supporting member, hydraulic means comprising a cylinder and a piston and a piston rod movable in the cylinder for moving the work positioning member between its operative and inoperative positions, control valve devices having pipe connections to said cylinder to supply pres-

sure medium to the latter under pressure and alternatively to connect the cylinder to an exhaust, a manually operable member to condition one control valve device whereby said piston and piston rod are caused to move to bring the work positioning member into its operative position, and automatically operating means for connecting another control valve device to said cylinder to project the piston and piston rod in the reverse direction thereby to move the work positioning member out of the path of the relative approaching movement of the work treating members.

18. In a machine for operating on shoe parts, a work supporting member, a member to cooperate with the first-mentioned member in work treating operations on a work piece, said members being relatively movable between work receiving and work treating positions, a work positioning member movable into the path of relative movement of said members to position parts of the work piece with respect to each other on said work supporting member, hydraulic means comprising a cylinder and a piston and a piston rod movable therein for moving the work positioning member between its operative and inoperative positions, control valve devices including a rotary control valve having pipe connections to said cylinder to supply pressure medium to the latter under pressure and alternatively to connect the cylinder to an exhaust, a manually operable member to condition one control valve device whereby said piston is caused to descend to bring the work positioning member into its operative position, and automatically operating means for connecting said rotary control valve to said cylinder to project the piston and piston rod in the reverse direction thereby to move the work positioning member out of the path of the relative approaching movements of the work treating members.

19. In a machine for operating on shoe parts, a work supporting member, a member to cooperate with the first-mentioned member in performing a treating operation on a work piece, a work positioning member, a work holddown member, means including a hydraulic mechanism and a manually operable control member therefor for bringing the work positioning and holddown members down in succession upon a work piece on the work support, means for initiating operation of the machine by which the upper work treating member is moved downwardly into cooperative relation with respect to the work supporting member, and means automatically operative through said hydraulic means to withdraw the work positioning and holddown members out of the path of the descending work treating member.

20. In a machine for operating on shoe parts, a work supporting member, a member to cooperate with the first-mentioned member in performing a treating operation on a work piece, a work positioning member, a work holddown member, means including a hydraulic mechanism and a manually operable control member therefor for bringing the work positioning and holddown members down in succession upon a work piece on the work support, said hydraulic means comprising a cylinder, a piston and piston rod movable in the cylinder and connected to operate the work positioning and holddown members, means for initiating operation of the machine by which the upper work treating member is moved downwardly into cooperative relation with respect to the work supporting member, and

means automatically operative through said cylinder to withdraw the work positioning and holddown members out of the path of the descending work treating member.

21. In a machine for operating on shoe parts, a work supporting member, a member to cooperate with the first-mentioned member in work treating operations on a work piece, a work positioning member, a work holddown member, means including a hydraulic mechanism and a manually operable control member therefor for bringing the work positioning and holddown members down upon a work piece on the work support, said hydraulic mechanism including a cylinder, a piston and a piston rod movable in said cylinder and connected to operate said work positioning and holddown members, a control valve device connected to said cylinder in said hydraulic mechanism, said manually operable member being movable in two successive steps in said control valve device to cause the work positioning member and the holddown member to move successively to operative position, and means automatically operative to return the work positioning member and the holddown member to inoperative position prior to movement of the upper work treating member into cooperative relation with respect to the work supporting member.

22. In a machine for operating upon shoe parts, a work supporting member, a member to cooperate with the first-mentioned member in performing operations on a work piece, said members being relatively movable between work receiving and work treating positions, a gripper for holding one element of the work piece in position on the work supporting member, a work positioning member movable into contact with said element of the work piece to position a second element in place with respect to the first element, a holddown also movable to hold the second element in position on the first element, hydraulic means including a manually controllable member for moving the gripper and the work positioning member to their operative positions, said manually controllable member being operative through said hydraulic means also to move the holddown to its operative position subsequently to the movement of the gripper and positioning member, and automatic means for controlling said hydraulic means to return the work positioning member and the holddown toward their inoperative positions during the relative approaching movement of the work treating members.

23. In a machine for operating upon shoe parts, a work supporting member, a member movable to cooperate with the first-mentioned member in performing treating operations on a work piece, a gripper for holding one element of the work piece in position on the work supporting member, a work positioning member movable into contact with said element of the work piece to position a second element in place with respect to the first element, a holddown also movable to hold the second element in position on the first element, manually controllable means for moving the gripper and the work positioning member to their operative positions, said manually controllable means having connections to move the holddown to its operative position subsequently to the movement of the gripper and positioning member, automatic means for returning the work positioning member and the holddown toward their inoperative positions

during movement of the second-mentioned work treating member toward the work supporting member, and means automatically operative upon separating movement of the work treating members at the end of a work treating operation to return the gripper to its inoperative or work receiving position.

24. In a machine for operating upon shoe parts, a work supporting member, a member movable to cooperate with the first-mentioned member in performing operations on a work piece, a gripper for holding one element of the work piece in position on the work supporting member, a work positioning member movable into contact with said element of the work piece to position a second element in place with respect to the first element, a holddown also movable to hold the second element in position on the first element, hydraulic means including a cylinder, a piston rod and a piston movable in said cylinder, said piston rod having operative connections with respect to said gripper, work positioning member and holddown, said hydraulic means including a control valve device for directing pressure medium under pressure to said cylinder and alternatively to connect the latter to an exhaust whereby the piston rod may be moved selectively in opposite directions, and a manually operable member movable in said control valve device to control the application of pressure to the piston in said cylinder to effect movement of the gripper member, of the work positioning member, and of the holddown in timed relation to each other to provide for positioning of the shoe part elements successively in relation to each other and holding them in assembled relation.

25. In a machine for operating upon shoe parts, a work supporting member, a member to cooperate with the first-mentioned member in performing operations on a work piece, a gripper member for holding one element of the work piece in position on the work supporting member, a work positioning member movable into contact with said element of the work piece to position a second element in place with respect to the first element, a holddown member also movable to hold the second element in position on the first element, manually controllable means for moving the gripper and the work positioning members to their operative positions, said manually controllable means having connections to move the holddown member to its operative position subsequently to the movement of the gripper and positioning members, automatic means for retracting the work positioning and the holddown members toward their inoperative positions during movement of the second-mentioned work treating member toward the work supporting member, and means for locking the gripper member in its operative or work contacting position so that it does not accompany the work positioning and holddown members in their retractive movement.

26. In a machine for operating upon shoe parts, a work supporting member, a member to cooperate with the first-mentioned member in performing operations on a work piece, a gripper member for holding one element of the work piece in position on the work supporting member, a work positioning member movable into contact with said element of the work piece to position a second element in place with respect to the first element, a holddown member also movable to hold the second element in position on the

first element, manually controllable means for moving the gripper and the work positioning members to their operative positions, said manually controllable means having connections to move the holddown member to its operative position subsequently to the movement of the gripper and positioning members, means for locking the gripper member in its operative position, means for returning the work positioning and holddown members toward their inoperative positions during movement of the second-mentioned work treating member toward the work supporting member, and means automatically operative upon separating movement of the work treating members to return the gripper member to its inoperative or work receiving position.

27. In a machine for operating upon shoe parts, a work supporting member, a member to cooperate with the first-mentioned member in performing operations on a work piece, a gripper member for holding one element of the work piece in position on the work supporting member, a work positioning member movable into contact with said element of the work piece to position a second element in place with respect to the first element, hydraulic means including a cylinder, a piston rod and a piston movable in said cylinder, said piston rod having operative connections with respect to said gripper and work positioning members, a control valve device for directing pressure medium under pressure to said cylinder and alternatively to connect the latter to an exhaust so arranged that the piston rod may be moved selectively in opposite directions, a manually operable member movable in said control valve device to cause movement of the gripper and the work positioning members to work contacting position, means for locking the gripper member in work contacting position, and means for moving the work positioning member to inoperative position before a work treating operation during which the gripper member remains in operation.

28. In a machine for operating upon shoe parts, a work supporting member, a member movable to cooperate with the first-mentioned member in performing operations on a work piece, a gripper for holding one element of the work piece in position on the work supporting member, a work positioning member movable into contact with said element of the work piece to position a second element in place with respect to the first element, a holddown also movable to hold the second element in position on the first element, hydraulic means including a cylinder, a piston rod and a piston movable in said cylinder and having connections to operate the gripper, the work positioning member and the holddown, said hydraulic means including also a control valve device having pipe connections to said cylinder whereby pressure medium under pressure may be supplied to move the piston and piston rod selectively in opposite directions, and a manually operable member movable in two successive steps to effect firstly through said control valve device movement of the gripper and the work positioning member to their operative positions, the second step movement of the manually operable member effecting through said control valve device a further movement of the piston and piston rod whereby the holddown is moved to operative position.

29. A machine according to the terms of claim 28 in which automatically operative means is provided to effect movement of the piston and

5 piston rod in the reverse direction whereby the holddown and work positioning members are moved out of the path of said second work treating member as the latter moves to cooperate with the work supporting member in work treating operations.

30. In a machine for operating upon shoe parts, a work supporting member, member to cooperate with the first-mentioned member in performing operations on a work piece, a gripper member for holding one element of the work piece in position on the work supporting member, a work positioning member movable into contact with said element of the work piece to position a second element in place with respect to the first element, a holddown member also movable to hold the second element in position on the first element, hydraulic means including a cylinder, a piston rod and a piston movable in said cylinder and having connections to move the gripper, the work positioning and the holddown members to their operative positions, a control valve device having pipe connections to said cylinder whereby pressure medium under pressure may be supplied to move the piston and piston rod selectively in opposite directions, a manually operable member in said control valve device movable downwardly in two steps through force exerted by the operator to effect, in the first downward step, movement of the gripper and the work positioning members to their operative positions, the second step movement of the manually operable member effecting through said control valve a further movement of the piston and piston rod whereby the holddown member is moved to operative position, and spring means to move said manually operable member in the reverse direction whereby upon reversing the step movements of said manually operable member the holddown member is 40 first moved upwardly to release said second work piece element and in the second reverse step movement the work positioning member is moved upwardly to release the first element of the work piece.

31. A machine constructed according to claim 30 in which means is provided for locking said gripper member in its operative position so that it does not accompany the upward movement of the work positioning member during the reverse step movements of the said manually operable member.

32. A machine constructed according to claim 30 in which means is provided for locking said gripper member in its operative position so that it does not accompany the upward movement of the work positioning member during the reverse step movements of the said manually operable member, said locking means being manually releasable so that all elements of the work piece may be released for repositioning on the work supporting member.

33. A machine constructed according to claim 30 in which automatically operating means is provided for moving the work positioning and holddown members to their retracted positions before a work treating operation takes place.

34. A machine constructed according to claim 30 in which means is provided for locking said gripper member in its operative position so that it does not accompany the upward movement of the work positioning member during the reverse step movements of the said manually operable member, means being also provided to return said work positioning and holddown members automatically to retracted position before a work

treating operation takes place, the arrangement being further such that means is provided to return the gripper member to its retracted or inoperative position during separating movement of the work treating members to release the finished work piece.

35. In a machine for operating upon shoe parts, a work supporting member and a cooperating member relatively movable with respect to each other in performing operations on a work piece, a gripper for holding one element of the work piece in position on the work supporting member, a work positioning member movable into contact with said element of the work piece to position a second element in place with respect to the first element, a holddown also movable to hold the second element in position on the first element, hydraulic means including a cylinder, a piston rod and a piston movable in said cylinder and having connections to operate the gripper, the work positioning member and the holddown, control valve devices including a rotary valve device having pipe connections to said cylinder whereby pressure medium under pressure may be supplied to move the piston and piston rod selectively in opposite directions, one of said control valve devices comprising a cylinder and a piston movable therein, a manually operable member connected to said piston and movable in two steps to effect through said control valve device, in the first step, movement of the gripper and the work positioning member to their operative positions, the second step movement of the manually operable member effecting through said control valve device a further movement of the piston and piston rod whereby the holddown is moved to operative position, and means operating through said rotary valve device for automatically returning the work positioning and holddown members to initial position.

36. A machine according to the terms of claim 35 in which movement of the piston in said control device in the reverse direction has the effect of moving the holddown member and the work positioning member in the reverse order toward their inoperative positions whereby one or more of the elements of the work piece may be readjusted in their reverse order at the will of the operator.

37. In a twin machine, each unit of which includes work treating members relatively movable between work receiving and work treating positions, each machine unit including also a work positioning member movable into the path of relative movement of said members to position parts of a work piece with respect to each other on one of said work treating members, hydraulic means including two operating units for the work positioning members of the two machine units, each operating unit being operative to move the work positioning member to its operative or work contacting position, a control valve device associated with both said operating units, a manually operable member movable in said control valve device to cause operation of one or the other of said operating units whereby a work positioning member is moved to its operative position under control of the operator, and automatic means operative to cause said hydraulic means to return the work positioning member toward its inoperative or rest position during relative movement of the work treating members into work treating position.

38. A machine constructed according to claim 36 in which said automatic means operates

through one of said operating units to retract its associated work positioning member to inoperative position, said automatic means also operating to condition the other operating unit for control by said manually operable member operating through said control valve device to move the other work positioning member to its operative position preliminary to treatment of a work piece in the other of the two machine units.

39. In a twin machine, each unit of which includes work treating members relatively movable between work receiving and work treating positions in performing operations on a work piece, each machine unit including also a work positioning member movable into the path of relative movement of said members to position parts of the work piece with respect to each other on one of said work treating members, hydraulic means under control of the operator for causing the recited movements of the work treating members, said hydraulic means including also two operating units for the work positioning members of the twin machines, a manually controlled valve device associated with both said operating units whereby the work positioning member associated with one of said units may be moved to its operative position under control of the operator, said hydraulic means including a second valve device operated in timed relation to the relative work treating movement of the work treating members of the selected one of the machines to return the work positioning member toward its inoperative or rest position during such relative movement of said work treating members, said second valve device being simultaneously operative to condition the other operating unit associated with the other of the two machine units for manual control to bring the work positioning member of that machine to operative position in assembling a work piece in said machine.

40. In a twin machine, each unit of which includes work treating members relatively movable between work receiving and work treating positions, each machine unit including also a work positioning member movable to engage a shoe part to position it on one of the work treating members preliminarily to a work treating operation, hydraulic means including two independent operating units for the work positioning members of the twin machines, said hydraulic means including also two control valve devices, of which one is a rotary valve device, in circuit with both of said operating units, a manually operable member having connections with one of said control valve devices to effect through one of said operating units movement of the associated work positioning member into work contacting position, and means operating in timed relation to its associated work treating member and through the said rotary valve device to effect, through the said one of the operating units, movement of its associated work positioning member to its inoperative position in advance of a work treating operation by said associated work treating members, said rotary valve device being operative at the same time to condition the other operating unit for control by said manually operable member when the other of the two machine units is to be utilized at the will of the operator in a work treating operation.

41. In a twin machine, each unit of which includes work treating members relatively movable between work receiving and work treating positions, each machine unit including also a work

positioning member movable to engage a shoe part to position it on one of the work treating members preliminarily to a work treating operation, hydraulic means including two independent operating units for the work positioning members of the twin machines, each operating unit including a piston, a piston rod, and a cylinder in which the piston and piston rod operate, said piston rod being connected to operate its associated work positioning member, said hydraulic means including also control valve devices having pipe connections to both said cylinders to operate the pistons therein in reverse directions, a manually operable member having connections with one of said control valve devices to effect through one of said operating units movement of the associated work positioning member into work contacting position, and means automatically operative through the other control valve device to effect movement of the piston and piston rod in one of said units in the direction to restore the said associated work positioning member to its inoperative position in advance of a work treating operation by said work treating members and at the same time to condition the other unit for control by said manually operable member when the other of the two machine units is to be utilized at the will of the operator in a work treating operation.

42. In a twin machine, each unit of which includes work treating members relatively movable between work receiving and work treating positions, each machine unit including also a work positioning member movable to engage a shoe part to position it on one of the work treating members preliminarily to a work treating operation, hydraulic means including two operating units for the work positioning members of the twin machines, each operating unit including a piston, a piston rod, and a cylinder in which the piston and piston rod operate, said piston rod being connected to operate its associated work positioning member, said hydraulic means including also control valve devices, of which one is a rotary valve device, having pipe connections to both said cylinders to operate the pistons therein in reverse directions, a manually operable member having connections with one of said control valve devices to effect through one of said operating units movement of the associated work positioning member into work contacting position, and means automatically operative through the rotary valve device to effect movement of the piston and piston rod in one of said operating units in the direction to restore the associated work positioning member to its inoperative position in advance of a work treating operation by said work treating members, said rotary valve device being operative at the same time to condition the other operating unit for control by said manually operable member when the other of the two machine units is to be utilized at the will of the operator in a work treating operation.

43. In a twin machine, each unit of which includes work treating members relatively movable between work receiving and work treating positions, each machine unit including also a work position members movable to engage a shoe part to position it on one of the work treating members preliminarily to a work treating operation, hydraulic means for effecting the recited relative movements of the work treating members, said hydraulic means including also two operating units for the work positioning members of the twin machines, each operating unit in-

cluding a piston, a piston rod, and a cylinder in which the piston and piston rod operate, said piston rod being connected to operate its associated work positioning member, said hydraulic means including also two control valve devices having pipe connections to both said cylinders to operate the pistons therein in reverse directions, a manually operable member having connections with one of said control valve devices to effect through a selected one of said operating units movement of the associated work positioning member into work contacting position, and means movable with its associated work treating member and operative to condition another control valve device thereby to effect movement of the piston and piston rod in said cylinder in the associated operating unit in the direction to restore the work positioning member to its inoperative position in advance of a work treating operation by said associated work treating member, the last-mentioned control valve device being operative at the same time to condition the other operating unit for control by said manually operable member when the other of the two machine units is to be utilized at the will of the operator in a work treating operation.

44. In a twin machine, each unit of which comprises work treating members relatively movable between work receiving and work treating positions, each machine unit comprising also a gripper member for engaging and holding on one of said work treating members the first element of a shoe part to be treated, a work positioning member movable to engage said first element of the shoe part to position a second element thereon, and a holddown member to hold the elements in assembled relation, hydraulic means including two operating units for the gripper and the work positioning and holddown members of the twin machine, each operating unit comprising a piston, a piston rod, and a cylinder in which the piston and piston rod operate, said hydraulic means including also control valve devices having pipe connections to both said cylinders to operate the pistons therein in reverse directions, a manually operable member having connections with one of said control valve devices to effect through one of said operating units movement of the gripper member, of the work positioning member, and of the holddown in succession into work contacting positions, and means automatically operative through another control valve device to effect movement of the piston and piston rod in one of said units in the direction to restore the work positioning member and the holddown to their inoperative positions in advance of a work treating operation by said work treating members and at the same time to condition the other operating unit for control by said manually operable member when the other of the two machine units is to have a work piece assembled in relation thereto as a preliminary to a work treating operation.

45. In a machine for operating upon pieces of work, a work support, a gage member to position a piece of work with respect to the work support, said gage member when in operative position projecting above the level of the work supporting surface of the work support, an ejector movable above the plane of the work supporting surface and in a direction substantially parallel to said surface for ejecting a treated work piece, and means to withdraw said gage member and to hold it stationary in retracted position for a definite period during which the ejec-

tor is operated, so that the gage member offers no obstruction to the ejection of the work piece.

46. In a machine for operating upon pieces of work, a work support, a gage member to position a piece of work with respect to the work support, said gage member when in operative position projecting above the level of the work supporting surface, an ejector movable above the plane of the work supporting surface and in a direction substantially parallel to said surface for ejecting a treated work piece, a member movable toward and from said work support to operate on the work piece, and means controlled by the work treating member to withdraw the gage and lock it in retracted position for a definite period during which said member moves away from the work support to release the treated work piece, the ejector operating in timed relation to said work treating member and to the gage so that said gage offers no obstruction to the ejection of the treated work piece.

47. In a machine for operating upon pieces of work, a work support, a gage member to position a piece of work with respect to the work support, said gage member when in operative position projecting above the level of the work supporting surface, an ejector movable above the plane of the work supporting surface and in a direction substantially parallel to said surface for ejecting a treated work piece, a work treating member movable in directions toward and from the work support to operate on a piece of work on the support, means operated by said work treating member to withdraw said gage from its operative position and to lock it in retracted position, and means controlled by said work treating member during its movement away from the work support to effect release of the locking means for the gage and to cause operation of the ejector in timed relation to each other so that the gage returns to its operative position only after operation of the ejector.

48. In a machine for operating upon pieces of work, a work support, a gage member to position a piece of work with respect to the work support, said gage member when in operative position projecting above the level of the work supporting surface, an ejector movable above the plane of the work supporting surface and in a direction substantially parallel to said surface for ejecting a treated work piece, a work treating member movable toward and from the work support to operate on a piece of work while the latter is backed by the work support, means operated during the operative stroke of the work treating member to retract said gage and to lock it in retracted position, and means operated during the movement of the work treating member away from the work support to effect operation of said ejector and also release of the locking means for the gage in such timed relation to each other that the gage returns to its operative position only after the work piece has been ejected.

49. In a press for treating shoe parts, a work support, a presser member movable toward and from the work support to cooperate with the latter in work treating operations, side gage members to locate a shoe part on the work support, means operated during the operative stroke of the presser member to retract said side gages and to lock the latter in retracted position, an ejector movable in a plane above and substantially parallel to the supporting surface of the work support to eject a treated piece of work, and

means operated during the movement of the presser member away from the work support to effect operation of the ejector and also release of the gage members so that the gage members return to gaging position only after the ejector has ejected the work piece.

50. In a machine for operating upon shoe parts, a work supporting member, a gage and means for adjusting the gage both mounted on said work supporting member, a mold member mounted upon the machine frame, said frame having a recess into which said work supporting member is receivable to be supported with its work supporting surface at a predetermined angle to the work supporting surface of said mold member, and a spacer block adapted to be received in said recess in the machine frame and having an upwardly facing recess into which said work supporting member is receivable to be supported at a different angle with respect to said mold member.

51. In a machine for operating upon shoe parts, a work supporting member, a second work supporting member adjustable in different angular relationships to the first supporting member, a machine frame having a recess in which the adjustable work supporting member is receivable to be supported with its work supporting surface at a predetermined angle to the surface of the first-mentioned work supporting member, and a spacer block receivable in said recess of the frame and having an upwardly facing recess to receive and support the second-mentioned work supporting member at a different angle from that first-mentioned whereby portions of a given work piece may be supported for treatment upon work supporting surfaces having a variable conformation.

52. In a machine for operating upon shoe parts comprising cooperating upper and lower work treating members of which the lower is mounted stationary upon the machine frame, the combination of a work supporting member, work positioning and holding means mounted on said work supporting member, said frame having a recess into which said work supporting member is receivable to be supported with its work supporting surface at a predetermined angle to the work supporting surface of said lower work treating member, and a spacer block adapted to be received in said recess in the machine frame and having an upwardly facing recess into which said work supporting member is receivable to be supported at a different angle with respect to said work treating member.

53. In a machine for operating upon shoe parts, a work backing member mounted stationary in a machine frame, a work treating member movable toward and from said backing member, a work supporting member adjustable in different angular relationships to the work backing member, the machine frame having a recess in which the adjustable work supporting member is receivable to be supported with its work supporting surface at a predetermined angle to the surface of the work backing member, and a spacer block receivable in said recess of the frame and having an upwardly facing recess to receive and support said work supporting member at a different angle from that first-mentioned whereby portions of a given work piece may be supported for treatment upon combined work backing and work supporting surfaces having a variable conformation.

JOSEPH C. CANTLEY.
